UNITED STATES PATENT OFFICE.

HENRY KREISINGER, OF PIERMONT, NEW YORK, ASSIGNOR TO COMBUSTION ENGINEERING CORPORATION, OF NEW YORK, N. Y., A CORPORATION OF NEW YORK.

PULVERIZATION OF COAL.

Application filed January 16, 1925. Serial No. 2,718.

To all whom it may concern:

Be it known that I, HENRY KREISINGER, a citizen of the United States, residing at Piermont, in the county of Rockland and 5 State of New York, have invented certain new and useful Improvements in the Pulverization of Coal, of which the following is a specification.

This invention relates to the pulverization 10 of fuel, such, for example, as coal used for burning in furnaces.

One of the primary objects of my invention is to simplify and materially reduce the cost of preparation and pulverization of the 15 coal. In this connection a very large item of expense is the drying of the coal which has inherent moisture and also, very frequently, considerable surface moisture. Usually the content of inherent moisture is 20 such as to introduce difficulties not only with respect to the preparation and handling of the coal, but also its use. The surface moisture adds to the complications. Heretofore, it has been the general practice to dry the 25 coal while in lump form to drive off all of the moisture it is desired to remove. This involves the application of more heat than I have found to be necessary and involves expense which I have discovered I am enabled to greatly reduce.

How the foregoing, together with such other objects as may hereinafter appear, or are incident to my invention, are realized, is set forth in the accompanying description 35 of the invention and the apparatus for carrying out the same illustrated in the drawings, wherein—

Fig. 1 is a side elevation of one form of apparatus or system suitable for practicing 40 my invention;

Fig. 2 is a diagrammatic side elevation of a modification of a detail of the invention; and

Figs. 3 and 4 are fragmentary side elevations illustrating still other modifications of the invention.

Referring now to the drawings, and particularly to Fig. 1 thereof, it will be seen that from a suitable source of supply of raw 50 coal, such as the bunker or bin 7, I conduct the coal to be crushed to a mill 8 from which a pipe 9 leads to a separator 10, the coal pulverized in the mill being conducted to the separator by a current of air set up by the fan 11, the coal and air being separated

in the separator 10, from which the separated coal is discharged to a bin 12 from which it may be transported or led to the burners of a furnace or to a storage bin, not shown.

In the preferred practice of my invention, there is a return pipe 13 from the separator to the mill, providing a substantially closed circuit.

I apply or supply heat for the system at a suitable point. The amount of heat I supply is that which, in the pulverization, will evaporate the desired amount of moisture in association with the current of air passing thru the system, which air absorbs such moisture. This proceeds upon the principle 65 that far much less heat is required to dry the coal when it is pulverized, and, or undergoing pulverization, than is required to drive off sufficient moisture when the coal is in lump form.

According to one form of my invention I pass the coal leaving the bunker 7 thru a heater 14, in which steam or some other suitable heating medium is applied. In passing thru the heater I do not attempt to drive off all of the moisture in the manner heretofore practiced, but propose to heat the coal only to the point where the sensible heat remaining in the coal, upon its introduction into the mill, is such, in association 75 with the current of air, as will drive all the necessary amount of moisture. In this connection, it will be seen that when the coal is in a finely divided condition the sensible heat carried by the coal will be such as to evaporate the moisture to the desired extent. In order to keep down the amount 80 of heat required, I locate the heater 14 comparatively close to the mill 8.

The air, which lifts the pulverized coal 95 from the mill 8 thru separator 10, absorbs the moisture and as it is being recirculated continually, the moisture content would rise so high that the air will become saturated, thereby rendering further operation impossible. To overcome this, I draw off from the return side of the separator, as thru the pipe 15, a certain proportion of the total air within the system and replace this by make-up gas, preferably in the form of dry air introduced thru the pipe 16 under control of the valve 17, the air introduced thru the pipe 16 being led to the mill. By way of specific illustration, the mill shown in Fig. 1 passes about 8,000 cubic feet per 100

minute therethru, and I draw off thru the pipe 15 about 2000 cubic feet of moisture laden air per minute, admitting approximately 2000 cubic feet per minute of make-up air thru the pipe 16. In this connection, the air which may enter with the coal is more or less negligible for the reason that the bunker usually has a substantial layer of coal in the bottom thereof, acting to some extent as a seal. In substitution of, or in supplementation of the heater 14, I may admit preheated air thru the pipe 16. If this air is sufficiently hot, then preheating of the coal may be dispensed with, or, if it is desired to partially heat the coal leaving the bunker, the balance of the heat may be supplied with the air to the pipe 16.

As an alternative hot flue gas may be supplied from the stack 18, under control of the valve 19. Thus by the arrangement shown in Fig. 1, by closing or opening, or partly closing or opening the valves 20, 17 and 19, all of the heat required may be supplied to the coal as it leaves the bunker; all of the heat may be supplied directly to the mill; or part of the heat required may be supplied at the heater 14 and part at the mill; or flue gas or hot air, or a mixture of the two, may be utilized in substitution of the heater 14 in whole or in part. When all of the heat required is supplied with the air or the flue gas and introduced into the mill, it will be seen that such heat is most effectively supplied and the amount required will be comparatively very small because of the fine state of division of the coal.

In the arrangement shown in Fig. 3, the heat is supplied by means of a steam or other heating coil 21, located around the mill. This is not as desirable as the arrangement previously described.

In the arrangement of Fig. 4, the air supplied for make-up purposes is preheated by passing over a steam or other heating coil 22. According to this arrangement, additional heat may be applied to advantage on the return side of the system by leading the return pipe 13 thru a steam or other form of heater 23.

I prefer in all arrangements, that the return air shall be somewhat less than 200° F.

From the foregoing description my invention, in so far as process is concerned will be understood.

I claim:

1. The herein described process of pulverizing coal which consists in pulverizing the coal in the mill of a system including a separator and air as a carrying medium, and in preheating the coal to be pulverized to a point such that the sensible heat of the coal in pulverization is sufficient to dry the coal for transport and in the presence of the carrying air.

2. The herein described process of pul-

verizing coal which consists in pulverizing the coal in the mill of a closed system including a separator and air as a carrying medium; in preheating the coal to be pulverized to a point such that the sensible heat thereof will dry the coal in pulverization in the presence of the carrying air stream, and in withdrawing and replacing sufficient of the moisture laden air to allow the process to continue. 75

3. The herein described process of pulverizing coal which consists in pulverizing the coal in the mill of a closed system including a separator and air as a carrying medium; in preheating the coal to be pulverized to a point such that the sensible heat thereof will dry the coal in pulverization in the presence of the carrying air stream, and in withdrawing and replacing sufficient of the moisture laden air to allow the process to continue, the makeup being in the form of a heated gaseous medium. 80

4. The herein described process of pulverizing coal which consists in pulverizing the coal in the mill of a closed system including a separator and air as a carrying medium; in preheating the coal to be pulverized to a point such that the sensible heat thereof will dry the coal in pulverization in the presence of the carrying air stream, and in withdrawing and replacing sufficient of the moisture laden air to allow the process to continue, the makeup being in the form of a heated gaseous medium, all with the maintenance of temperature conditions such that detrimental condensation in the separated coal is avoided. 95

5. In a fuel pulverizing system, a mill, a separator, suitable piping between mill and separator and separator and mill, means for setting up an air current within the system, a source of supply of fuel to be pulverized, means for introducing heat into the system, and means for withdrawing moisture laden gas from the system. 105

6. In a fuel pulverizing system, a mill, a separator, suitable piping between mill and separator and separator and mill, means for setting up an air current within the system, a source of supply of fuel to be pulverized, means for introducing heat into the system with the coal, and means for withdrawing moisture laden gas from the system. 110

7. In a fuel pulverizing system, a mill, a separator, suitable piping between mill and separator and separator and mill, means for setting up an air current within the system, a source of supply of fuel to be pulverized, means for introducing heat into the system through the mill, and means for withdrawing moisture laden gas from the system. 120

8. In a fuel pulverizing system, a mill, a separator, suitable piping between mill and separator and separator and mill, means for setting up an air current within the system, 130

a source of supply of fuel to be pulverized, means for withdrawing moisture laden gas from the system and means for supplying make-up for the system, said make-up carrying heat.

9. In a fuel pulverizing system, a mill, a separator, suitable piping between mill and separator and separator and mill, means for setting up an air current within the system, a source of supply of fuel to be pulverized, means for introducing hot flue gas into the system, and means for withdrawing moisture laden gas from the system.

10. In a fuel pulverizing system, a mill, a separator, suitable piping between mill and separator and separator and mill, means for setting up an air current within the system, a source of supply of fuel to be pulverized, means for introducing heat into the system from the burning of the product of the system, and means for withdrawing moisture laden gas from the system.

11. In combination in a fuel preparing system, a source of coal supply, a mill, a

separator, piping from the mill to the separator, means setting up a carrying current of gas through the system, and means for introducing heat into the system whereby in pulverization sufficient moisture is evaporated and taken up by the gas.

12. In combination in a fuel preparing system, a source of coal supply, a mill, a separator, piping from the mill to the separator, means setting up a carrying current of gas through the system, and means for introducing heat into the system whereby in pulverization sufficient moisture is evaporated and taken up by the gas, together with return piping from the separator to the mill, means for withdrawing sufficient of the moisture laden gas from the system to prevent the moisture content from unduly rising, and means for supplying make-up.

In testimony whereof, I have hereunto signed my name.

HENRY KREISINGER.
